(57) **CLAIM**

An ornamental design for a hand guard with internal rail mounts, as shown and described.

DESCRIPTION

FIG. 1 is a perspective view of a first embodiment a hand guard showing our new design and illustrative top Picatinny rail, rear accessory load gap, and rifle accessories mounted in dual internal rail mounts;

FIG. 2 is a front plan view of the hand guard with the dual internal rail mounts of FIG. 1 showing our new design and illustrative top Picatinny rail and rifle accessories mounted in the dual internal rail mounts;

FIG. 3 is a rear plan view of the hand guard with the dual internal rail mounts of FIG. 1 showing our new design and illustrative top Picatinny rail and rifle accessories mounted in the dual internal rail mounts;

FIG. 4 is a top plan view taken from the uppermost side of FIG. 1 showing our design and the illustrative top Picatinny rail;

FIG. 5 is a bottom plan view taken from the lowermost side of FIG. 1 showing our design and the illustrative rear accessory load gap;

FIG. 6 is a side plan view taken from the right side of FIG. 1 showing our design and the illustrative top Picatinny rail and the rear accessory load gap;

FIG. 7 is a perspective view of second embodiment a hand guard showing our new design and illustrative top Picatinny rail, rear accessory load gap, and rifle accessories mounted in treble internal rail mounts;

FIG. 8 is a front plan view of the hand guard with the treble internal rail mounts of FIG. 7 showing our new design and the illustrative top Picatinny rail and the rifle accessories mounted in the treble internal rail mounts;

FIG. 9 is a rear plan view of the hand guard with the treble internal rail mounts of FIG. 7 showing our new design and the illustrative rifle accessories mounted in the treble internal rail mounts;

FIG. 10 is a top plan view taken from the uppermost side of FIG. 7 showing our design and the illustrative top Picatinny rail;

FIG. 11 is a bottom plan view taken from the lowermost side of FIG. 7 showing our design and the illustrative rear accessory load gap; and,

FIG. 12 is a side plan view taken from the right side of FIG. 7 showing our design and the illustrative top Picatinny rail and the rear accessory load gap.

The Picatinny rail, rear accessory load gap, and rifle accessories (drawn with phantom line) in FIGS. 1–12 are provided for illustrative purposes only and are not considered part of the design.
